(57) CLAIM

The ornamental design for a flossing device, as shown and described.

DESCRIPTION

FIG. 1 is a front perspective view of the flossing device; FIG. 2 is a bottom elevation view of the flossing device of FIG. 1;

FIG. 3 is a top elevation view of the flossing device of FIG. 1;

FIG. 4 is a right side elevation view of the flossing device of FIG. 1;

FIG. 5 is a left side elevation view of the flossing device of FIG. 1;

FIG. 6 is a front plan view of the flossing device of FIG. 1; and,

FIG. 7 is a rear plan view of the flossing device of FIG. 1. The broken lines in the drawing are for illustrative purposes only and form no part of the claimed design.
